UNITED STATES PATENT OFFICE.

MILLARD P. OSBOURN, OF PHILADELPHIA, PENNSYLVANIA.

REFRIGERATING SYSTEM.

Application filed August 13, 1920. Serial No. 403,332.

To all whom it may concern:

Be it known that I, MILLARD P. OSBOURN, a citizen of the United States, and a resident of the city of Philadelphia, in the county of Philadelphia, and State of Pennsylvania, have invented certain new and useful Improvements in Refrigerating Systems, of which the following is a specification, reference being had to the accompanying drawing.

My invention relates to a system of refrigeration based upon the principle of heat extraction by evaporation of a part of the refrigerant by a constantly maintained high vacuum. For the purpose of more clearly illustrating the application thereof, I have herein described, and shown on the accompanying drawing, a few embodiments of my invention in apparatus adapted to carry out the principles of my invention.

One of the objects of this invention is to provide a novel and useful refrigerating system or apparatus of simple construction and of unitary organization.

Another object is to so construct such a system or apparatus whereby the refrigerating effects, temperature depressions or heat abstractions may be accomplished wholly by a comparatively simple and reliable mechanical means without the utilization or the intervention of any chemical or chemical reactions and with the elimination of the complicated and cumbersome devices heretofore found essential to reach similar ends.

One of the principal objects of this invention is to provide a system of refrigeration or a refrigerating apparatus adapted to operate upon the principle or known law of nature that the evaporation of a liquid, such as water or solutions composed mainly of water and a dissolved substance, effects a cooling thereof, if the solution be not supplied with heat from an available source.

Another object is to provide the aforesaid system or apparatus with means, in the attainment of the results incidental to refrigeration, capable of rapidly and efficiently abstracting or absorbing heat from the refrigerant or cooling medium.

A still further object is to provide such system or apparatus with means adapted to produce a high vacuum or very low absolute pressure corresponding to the vapor tension of the liquid or refrigerant at any desired temperature.

Still further objects and advantages are to provide a system or apparatus which is capable of great capacity; will occupy very little space; be comparatively cheap to construct, involving extremely low first cost of installation; operate very economically with practically no wear and tear and practically automatically when once set in operation; require very little or no attention or attendance; be perfectly safe and free of any danger, as from explosions, requiring no pressure higher than that of the atmosphere; requiring no chemicals, avoiding any recharging and eliminating practically all losses by leakage, corrosion, deterioration and the like; reduce the cost of repairs and maintenance to an inconsequential or negligible quantity; operate at a very small expense of energy or power; do away with the use of steam ejectors or other steam appliances of any kind, condensers, air pumps, circulating pumps, cooling towers, cooling coils, turbines and the like, and operate with an extremely high efficiency.

A still further object is to provide the system or apparatus with means to render non-available any supply of heat from the exterior of the system or apparatus other than from the device or articles upon which the refrigerant or cooling medium imposes its cooling effect, such as a refrigerator containing food and similar goods; such means being preferably in the nature of a vacuum jacket and being so constructed that the vacuum thereof will be self-created and self-sustained from the operation of the system or apparatus.

A still further object is to construct the apparatus for operation at pressure below that of the atmosphere, thereby avoiding the danger of explosions, leakage and the like.

Such other objects and advantages that are present in my invention will more fully appear in the following specification and upon the accompanying drawing.

For the purpose of making clear the law of nature involved, reference is made to the fact that any liquid, when vaporizing, must be supplied with heat, and, if no other source of heat is available, it will be drawn from the liquid itself, which is consequently cooled.

By my system, the substance to be cooled, which may be water, brine or any aqueous solution (calcium chlorid may be used in-

stead of salt or sodium chlorid), is cooled directly within the apparatus without the use of a separate cooler, nor of a series of devices for producing a vacuum, such as 5 steam ejectors, condensers and air pumps, and the auxiliaries thereto.

My invention therefore is not limited, nor is it intended to be limited, to merely refrigeration, as it is and will be apparent from 10 the herein disclosure.

Referring more particularly to the drawings, in which corresponding reference characters are used to designate corresponding elements in the figures shown,

15 Fig. 1 is a vertical transverse section of one form of refrigerating apparatus, constructed in accordance with the invention; and

Fig. 2 is a similar view of another form.

20 Referring now more particularly to the drawing, the embodiment shown in Fig. 1 comprises a refrigerator 1 having therein a refrigerating compartment 2. Within this compartment is located a part of the refrigerating device, such device comprising a closed casing 3 provided with a tray or pan 4 and vertical partitions 5 and 6, dividing the tray space and the casing 3 into two parts and chambers. The lower portion of 25 the casing 3 contains a refrigerant or liquid 7, such as brine, and has connected thereto a liquid conduit 8 leading to a pump 9, the latter being a vacuum pump of the type disclosed and illustrated in my copending 30 application, Serial No. 400,175, filed July 30, 1920. This pump may be operated by a motor 10 connected to the shaft 11 of the pump. The pan or tray may be provided with a trap portion 12 for liquid sealing an 35 opening 13 formed between the lower end of the partition 5 and the bottom of the trap 12, the tray 4 being provided with a rim 14 in the chamber 15 of the casing 3 whereby a liquid may be contained in the 40 section of the pan 4 located in said chamber at a higher level than the section of the pan located in the chamber 16, the section of the pan in the latter chamber being provided with a low rim 17. The bottom of 45 the pan section in chamber 15 also may be provided with a plurality of perforations 18 through which the liquid may pour in the form of a rain or spray to the lower portion of the chamber 15. The partition 6 50 extends from the bottom of the trap 12 to a point proximate to the bottom of the casing 3 but providing a communication between the lower portions of the chambers 15 and 16. In the lower portion of the 55 chamber 16, above the liquid level thereof, may be provided a hood or cap 18' supported, in any suitable manner in position over a tapered inlet 19 of a vapor conduit 20, the latter leading to the pump 9. The 60 cap 18' is of use to prevent the entry of

liquid pouring over or falling from the tray section located over said cap. In the upper part of the chamber 16 may be located a Worthington rotary spray ejector 21 provided with a spraying nozzle 22 70 adapted to spray liquid into the section of the pan located in chamber 16. The ejector 21 may be provided with a short connection 37 leading through the wall 5 into the chamber 15 whereby vapor may be conducted 75 from said chamber to the ejector through said connection. From the ejector 21 also leads a conduit 23 to a receiving tank 24 located beneath the pump 9, the tank 24 being connected to the pump 9 by a discharge conduit 25. In the receiver 24 is normally contained a certain amount of liquid adapted to flow into the conduit 23 to the ejector 21. The passage of liquid to the conduit 23 may be controlled by a check valve 26 to 80 which is connected a rod 27 and a float ball 28, the check valve and the float means being mounted on a pivot 29, whereby, as the liquid level in the chamber 24 rises, the check valve 27 opens to permit entrance of the liquid into the conduit 23. If, however, the liquid level in the receiver 24 should fall below a certain level, it would be desirable to supply additional fluid or liquid to 85 said receiver. For this purpose, an auxiliary liquid supply conduit 30 is connected to the lower portion of the receiver 24 and the check valve 31 located in the receiver 24 to control the inward flow of liquid therefrom. This check valve is pivotally mounted 90 upon the pivot 32 and has connected thereto an arm 33 and a float ball 34. When the liquid level of the receiver 24 is lowered, the float ball 34 will fall and the valve 31 will open, whereby liquid supply from the conduit 30 may enter the chamber 24 and replenish the same. As the liquid level rises in the chamber 24, the float 24 will rise and the valve 31 close.

95 In operation, the motor drives the pump 110 at a rapid rate of rotation whereby a vacuum is produced in the conduit 20 and in the chamber 16, the effect of the vacuum being transmitted through the tapered inlet 19, around the cap 18' into the chamber 16. The effect of the vacuum is also transmitted 115 through the ejector 21 and the conduit 23 whereby the liquid in the receiver 24 will be forced through the conduit 23 into the ejector 24 where the same will be sprayed over the section of the pan located in the chamber 16. As the liquid is sprayed in 120 said chamber, the vacuum therein will cause a partial vacuum of the liquid whereby latent heat of vaporization is extracted, and consequently, the liquid in the pan will be of 125 lower temperature than that in the receiver 24. This liquid will pass into the trap 12 and into the section of the pan located in chamber 15 where the liquid may also pour 130

through the perforations 18 into the lower portion of the chamber 15. The vacuum in the chamber 16 will be transmitted to the chamber 15 through the ejector 21 and the connection 37, as well as through the communications between the walls 5 and 6 and the trap 12 and the bottom of the casing 3. The vacuum produced in chamber 15 will also be augmented by the action of the 5 ejector so that the vacuum therein will maintain the liquid levels in chamber 15 higher than in chamber 16. As the liquid pours through the perforations 18, the vacuum in the chamber 15 will cause a further evaporation of a portion thereof, thereby further cooling the liquid in said chamber. The cooled liquid will therefore absorb heat transmitted through the walls of the casing 3 whereby the air space in the compartment 10 will become lowered in temperature. The liquid in the lower portion of chamber 15 will then flow through the opening beneath the wall 6 into the lower portion of the chamber 16, thence into the conduit 8 to the 15 pump 9. It will be noted that the pump 9 is provided with an upwardly extending connection 35 which is open to the atmosphere, the pump 9 operating non-submerged, so that the fluids operated upon therein will flow 20 through the connection 25 into the receiver 24, the vapors mixed with the liquids in said pump disengaging therefrom within the pump or within the receiver 24 and passing upwardly through the connection or 25 pipe 35 to the atmosphere. It will thus be apparent that atmospheric pressure is present in the receiver 24 which will be effective to force the liquid thereof through the pipe 23 to the ejector 21 which is being subjected 30 to a high vacuum.

Referring to Fig. 2, the structure shown therein is a similar structure with the exception that instead of locating the device within a refrigerator, the same may be provided with a circulating pipe and a coil, the latter being located in a refrigerator. This device comprises an outer casing 2', within which is located an inner casing 3' having compartments or chambers 15' and 16', the 45 latter being open at the upper end thereof to the interior of the casing chamber 2', whereby a vacuum space 36 will be formed between the walls of the casing 3' and 2', thereby insulating the casing 3' from inflow of heat. The casing 3' may be provided with partitions 5' and 6' with the former extending into a trap 12' formed in the tray 4', the tray 4' being of the same form as that shown in Fig. 1 with one section 50 thereof located in the chamber 15' and the other section thereof located in the chamber 16'. The section located in the chamber 15' may be provided with a plurality of perforations 18'' through which liquid may 55 pour into the lower portion of the chamber 60

15'. The wall 6', however, extends to the bottom of the chamber 3' thereby cutting off communication between the two lower portions of the casing 3'. The pan section in the chamber 15' may also be provided 70 with a wide flange 14' and the other section in the chamber 16' provided with a narrow flange 17'. In the upper part of the chamber 16' may be located a Worthington rotary spray ejector 21' which may be provided 75 with a short connection 37' leading through the wall 5' into the chamber 15', and conduit 23' leading to a receiving chamber 24'. The ejector may also be provided with a spray head 22' for the purpose of spraying 80 liquids into the pan section located in the chamber 16'.

Below the latter pan section and in the lower portion of the chamber 16' may be mounted, in any suitable manner, a hood or cap 18''' 85 above a tapered inlet or intake 19' of a vapor conduit 20' leading to the vapor spaces of the pump 9', this pump being of the same type as that disclosed in my copending application, Serial No. 400,175, filed July 30, 1920. The cap 18''' prevents entry of liquid in the intake 19' as the liquid overflows the pan section in chamber 16'. From the lower portion of the chamber 16' leads a liquid conduit 8' connected also to the 90 pump 9'. The pump 9' may be also provided with a vent pipe or conduit 35' and a discharge pipe 25' leading into the receiving chamber 24'. Within the receiving chamber 24' may be pivotally mounted a check 95 valve 26' having an arm 27' and a float 28' adapted, upon rise of liquid level in the chamber 24', to cause an opening of the check valve 26' to permit the inflow of liquid 100 into the conduit or pipe 23' to the rotary ejector 21'. Within the same chamber may be also pivotally mounted a check valve 31' provided with an arm 33' and a float 34' adapted upon lowering of the liquid level to cause an opening of the check valve 31' to 105 permit inflow of replenishing liquid through the conduit 30' to supply the receiver 24' with liquid. The pump may be operated by a motor 10' driving the pump shaft 11'. It will be noted that the lower portion of the 110 chamber 15' may be connected by a conduit 38 leading to a coil 39 located in a chamber 40 of a refrigerator 41, the upper portion of the oil being connected by a conduit 42 leading to the interior of the chamber 16' above 115 the normal level of the liquid therein, the pipe or conduit 42 being normally below the level of the liquid in the chamber 15'.

The various conduits running to and from the pump and casings 2' and 3' may be insulated from heat in any suitable manner, as by covering the same with insulating material.

In operation, the pump 9' creates and maintains a vacuum through the conduits 120

20' and the chamber 16'. This vacuum will be transmitted through the opening at the top of the chamber 16' into the surrounding space 36 between the walls of the casings 2' and 3' thereby insulating the casing 3', and the chambers 15' and 16', therein from conduction of heat from the exterior of the apparatus. As the vacuum is formed and maintained in the chamber 16', it will be also effective on the spray ejected by the spray head 22' to evaporate a portion thereof, whereby latent heat of vaporization is extracted and the liquid flowing in the pan section located in the chamber 16' will be cooled. This liquid will flow through the trap 12' into the pan section located in the chamber 15'. In the chamber 15' is also created a vacuum which may be transmitted through the connection 37'. The vacuum in the chamber 15', however, will be greater than that in chamber 16' by reason of the fact that the Worthington rotary spray ejector will, upon its operation upon the liquid passing therethrough, cause an additional vacuum which will be transmitted through the connection 37' to the chamber 15'. Inasmuch as the vacuum in the chamber 15' is greater than in the chamber 16', the liquid level in the pan 4' will be higher in the former chamber. As the liquid pours through the perforations 18'' into the lower portion of the chamber 15', a portion thereof will be evaporated by the vacuum in said chamber whereby further latent heat of vaporization is given up and the liquid further cooled. The cooled liquid collected in the lower portion of the chamber 15' will flow through the conduit 38 into the coil 39 and conduit 42 into the chamber 16', such flow being caused both by the heating of the liquid in the coil 39 as well as by the difference in levels between the liquid in the chambers 15' and 16'. The liquid in the lower portion of the chamber 16' will then flow through the conduits 8' into the pump 9', where the same is again operated upon in the manner disclosed in my copending application heretofore referred to, the vapors disengaging from the liquids in said pump and passing off into the conduit 35' to the atmosphere, and the liquid passing through the conduit 25' into the receiver 24'. It will be noted that the pressure in the receiver 24' is that of the atmosphere, the pump operating non-submerged. Therefore, when the vacuum in the chamber 16' is created, its effect upon the ejector 21' and in the pipe conduit 23' is to permit the atmospheric pressure to force the liquid, in the receiver 24', into the conduit 23' and the ejector 21'.

Having thus described and shown upon the accompanying drawing certain embodiments constructed in accordance with my invention, it is however, to be understood that

the invention is not limited to the particular details and arrangement of parts shown and described, but that the invention comprehends other embodiments, details and arrangement of parts as do not depart from the spirit of the invention and the scope of the appended claims. 70

Having thus described my invention, what I claim and desire to protect by Letters Patent of the United States is: 75

1. In a refrigerating system the combination of a closed chamber divided into two compartments, the refrigerant forming a liquid seal between said compartments, a pump, a conduit from one of said chambers to said pump through which the refrigerant is conveyed from said chamber to said pump, a conduit from the upper part of said chamber over said refrigerant to said pump for conveying the air and vapors to said pump to produce a vacuum in said chamber, an ejector in said chamber, a conduit from said pump to said ejector through which the refrigerant is returned to said chamber, and a conduit from the upper part of said second compartment to said ejector for maintaining a vacuum in said second compartment above said refrigerant. 80

2. In a refrigerating system, the combination of a closed chamber, a substantially vertical partition dividing said chamber into a first and second compartment, a substantially horizontal tray or pan disposed on opposite sides of said partition, the opposite sides of said pan or tray being in communication through said partition by a water-trap passage, an ejector spray nozzle in the first compartment for raining a liquid refrigerant upon the portion of the pan or tray therein, a conduit extending from the upper part of the second compartment through said partition into the interior of said nozzle to draw gases and vapors from said second compartment into said first compartment, whereby the partial vacuum so formed in the second compartment draws the refrigerant from that portion of the pan in the first compartment through said trap into the portion of said pan in said second compartment to the bottom of said second compartment, and causes said refrigerant to rain from said portion of said pan in said second compartment to the bottom of said second compartment, means to positively continuously remove said refrigerant commingled with gas and vapor from the first compartment into a tank open to atmospheric pressure, and a conduit extending from said tank to said nozzle and through which said refrigerant is continuously returned to said first compartment. 95

3. In a refrigerant system, the combination of a closed chamber, a substantially vertical partition dividing said chamber into a first and second compartment, a sub- 100
105
110
115
120
125

stantially horizontal tray or pan disposed on opposite sides of said partition, the opposite sides of said pan or tray being in communication through said partition by a water-trap passage, an ejector spray nozzle in the first compartment for raining a liquid refrigerant upon the portion of the pan or tray therein and upon the bottom of said first compartment, a conduit extending from 10 the upper part of the second compartment through said partition into the interior of said nozzle to draw gases and vapors from said second compartment into said first compartment, whereby the partial vacuum so 15 formed in the second compartment draws the refrigerant from that portion of the pan

in the first compartment through said trap into the portion of said pan in said second compartment, and causes said refrigerant to rain from said portion of said pan in 20 said second compartment to the bottom of said second compartment, means to positively continuously remove said refrigerant commingled with gas and vapor from the first compartment into a tank open to atmospheric pressure, and a conduit extending from said tank to said nozzle and through which said refrigerant is continuously returned to said first compartment.

In witness whereof, I have hereunto set 25 my hand this 11th day of August, 1920.

MILLARD P. OSBOURN.
